WASTE SEPARATING SHAKER

Louis J. Schaefer, Milwaukee, Wis., assignor to Journal Box Servicing Corporation, Indianapolis, Ind., a corporation of Indiana

Application November 14, 1951, Serial No. 256,185

9 Claims. (Cl. 19—81)

This invention relates to a device for loosening and separating one from another strands and fibers of journal box waste which has previously been soaked in oil. The device finds particular use in the operations of cleaning used journal box waste through such processes as are embodied in the United States Patents Nos. 2,000,291 and 2,090,260.

In using the oil extracting mechanism of Patent No. 2,090,260 as shown in Fig. 6 therein, the waste will leave that extractor in a more or less matted and compressed condition. In leaving this extractor, the waste has previously been put through a dehydrating and a washing operation and then is to go on to a reoiling operation. The operation is better carried out if the waste is shaken loose and carried through the reoiling operation in a more or less separated fiber condition.

Heretofore, the matted and compressed waste in leaving the extracting device of this Patent No. 2,090,260 has been initially dumped into the reoiling device, but later dumped onto a shaking table where the waste would be pulled apart and separated by hand. Then the separated waste would be passed on into the reoiling mechanism.

The present device is installed between the waste extractor and the reoiling mechanism so that the process may be continuously carried on in an automatic sequence without having to interrupt the process by intervening hand operations.

A great advantage of the present invention lies in the fact that it will receive the matted and more or less pressed waste and gradually separate the fibers and loosen up the entire mass into a more or less fluffed up condition so that the waste will eventually be in a condition to receive oil quite readily. There must be a resilience to the waste body in order to make it effective when finally returned to journal boxes for use. In this present invention, the waste is restored to this loose and resilient condition by an operation which is exceedingly gentle in respect to the waste, that is the operation will not cut and break the fibers to any extent so that the fibers are not reduced in length.

The device will gently pull and shake up the waste until it is restored to the highly desired condition of being loose and resilient.

In describing the invention, reference is made to the accompanying drawings in which

Fig. 1 is a view of the device in front end elevation; Fig. 2 is a view in side elevation;

Fig. 3 is a view in top plan;

Fig. 4 is a view in top plan of the finger and interconnecting elements in disassembled relation;

Fig. 5 is a view in side elevation of one end finger element;

Fig. 6 is a view in side elevation of an opposite side finger element;

Fig. 7 is a view in side elevation of the waste receiving pan; and

Fig. 8 is a view in vertical section on the line 8—8 in Fig. 7.

A rectangular framework herein shown as being made out of angle bars is made out of the cross and side elements 10, 11, 12, and 13. This framework generally designated by the numeral 14 is supported by corner legs 15. Base legs 16 support the legs 15 in such a manner that the rear end bar 10 is held at a higher elevation than the front bar 11, the difference in elevation being

approximately five inches for an overall length of the device of approximately four feet.

A finger element generally designated by the numeral 17 is formed to have a bar 18. This bar 18 is provided with a plurality of long fingers 19, herein shown as 18 in number. Each of these fingers 19 is secured to the supporting bar 18 by any suitable means such as by welding and extends therefrom in a free, cantilever manner so that the ends 20 are free. These fingers 19 are spaced apart in parallel relation a suitable distance such as for example on two inch centers. Then behind the last finger 19, there is a series of shorter fingers 21 likewise carried by the supporting bar 18 to extend in parallel relation to the fingers 19 and in spaced apart relation to have the same spacing therebetween as that of the fingers 19. However, as compared to the length of the fingers 19, which is approximately twenty-six and three quarters inches from the bar 18 to the tip end 20, the shorter fingers 21 each have lengths of approximately eleven inches. In the form herein shown, there are seven of these shorter fingers 21.

There is provided a finger assembly generally designated by the numeral 22 to have the supporting bar 23 carrying the long fingers 24 and the series of shorter fingers 25, these fingers 24 and 25 corresponding in number to those carried by the bar 18.

There are fixed to the bar 18 a pair of spaced apart hinge arm assemblies 26 and 27 respectively, these arms being turned outwardly and upwardly from the bar 18 at an angle of substantially one hundred and thirty degrees. These assemblies 26 and 27 carry bearing ends 28 and 29 respectively which are rockably supported in the bearing blocks 30 and 31 which are mounted on the posts 15. Likewise the unit 22 has the spaced apart arm assemblies 32 and 33 to each carry the bearings 35 and 36 respectively to interengage in bearing blocks 38 and 37 respectively. Thus the finger assemblies 17 and 22 are rockably carried to swing below the top frame members 10, 11, 12, and 13.

These two assemblies 17 and 22 are rockably interconnected by means of a waste pan 39, this pan 39 consisting essentially of a flat plate with an outer upturned rear flange 40. The pan 39 carries at opposite ends a series of clips 41 and 42 respectively, each of these clips being identical, and having a circular eye 43 of widths which will permit the clips to slidably pass between the lower ends of the fingers 21 and 25 respectively, and receive a rod 44 and 45 through the eyes 43 respectively. The rods 44 and 45 pass through holes 46 and 47 provided through the lower ends of the fingers 21 and 25 respectively, Figs. 5 and 6.

On the underside of the pan 39 there is secured a pair of downturned brackets 48 and 49 spaced apart sufficiently to receive therebetween the end of an eccentric rod 50 to have the brackets 48 and 49 rockably support that rod 50 by means of a cross pin 51 which extends through holes 52 and 53 provided respectively in the brackets 48 and 49.

This eccentric rod 50 extends under the pan 39 and is connected to an eccentric 54 which is fixed on a fore and aft shaft 55 mounted to revolve along the outside of the legs 15 in the bearings 56 and 57. The eccentric 54 is secured to the rear portion of the shaft 55. A sprocket 58 is also fixed on this shaft 55 ahead of the eccentric 54 and carries a chain 59 which extends around a sprocket 60 fixed on an upper shaft 61 which is carried in parallel relation to the shaft 55 by the bearings 62 and 63.

On the front end of the shaft 61 there is fixed a pulley 64 around which extends a belt 65 from a pulley 66 mounted on the shaft of a driving motor 67. This motor 67 is mounted on a plate 68 which extends across the front end portions of the rails 12 and 13 and over the front rail 11.

On a number of the fingers 19 and 24 first appearing ahead of the short fingers 21 and 25 there are fixed longitudinally therealong and to extend upwardly therefrom in each instance a toothed comb 70 and 71 respectively. In the present showing, the first ten of the long fingers 19 and also 24 carry these combs 70 and 71 respectively, the succeeding fingers from then on to the discharging end are left without the combs. The lower

ends of the fingers 19 and 24 have their end portions 20 and 72 curved slightly upwardly as indicated in Figs. 1, 5, and 6. Across the rear bar 10 and the rear portions of the side bars 12 and 13, there is fitted a short downwardly and forwardly extending guide chute 73. The lower front edge 74 of this chute 73 is vertically disposed over the pan 39. The upturned flange 40 extending rearwardly and upwardly from the pan 39 is behind this edge 74, Fig. 3.

Operation

When waste is to be fed into the device described, the motor 67 is set into operation which will drive the shaft 61 and in turn drive the lower shaft 55 at a speed reduced from that of the motor since the pulley 64 is larger than the pulley 66, and likewise the sprocket 58 is larger than the sprocket 60. Turning of the shaft 55 will cause the eccentric 54 to revolve and thus reciprocate the eccentric rod 50 in a generally transverse direction across the device, and thus will reciprocate the pan 39 accordingly. As the pan 39 is reciprocated, Fig. 1 it will rock from the solid line position which is the position at the extreme right hand end of travel, to the dash line position which is substantially the extreme end of the left hand travel, the chute 73 being at the rear end. Waste is then dropped down over the chute 73 to allow it to fall initially between the finger assemblies 21 and 25 to drop onto the pan 39, and as the assemblies 21 and 25 are rocked from the full line positions to the dash line positions and the reverse as indicated in Fig. 1, the waste on this pan will tend to be kicked from side to side as well as bounced upwardly slightly, and since the finger assemblies 21 and 25 are inclined as indicated in Fig. 2, the waste will tend to fall forwardly along the fingers 19 and 24.

As the waste leaves the pan 39, the combs 70 and 71 will engage in the waste and will gently tend to hook into the matted fibers of the waste and pull them out into straight-end conditions by the waste fibers hooking over the teeth of these combs. The pulling apart is relatively slow, and is reversed since the comb 70 will initially be in an upward position with the comb 71 in a lower position, to carry the comb 70 downwardly and the comb 71 upwardly as the finger assemblies are rocked. The curved lower ends 20 and 72 of the fingers 19 and 24 tend to prevent the waste from dropping through between these lower ends so that the waste is gently carried outwardly and downwardly from between the fingers to discharge from the outer extreme fingers 19a and 24a, Fig. 4. By reason of the offset arrangement of the mounting of the supporting bars 18 and 23 in reference to the bearings upon which the assemblies 17 and 22 swing, the teeth 19 and 24 are relatively spread apart by their upper ends in that swinging action as will be noted by the travel for instance of the fingers 19 from the solid line to the dash line positions. The axes of the bars 18 and 23 are in a plane parallel to the top sides of the side bars 12 and 13. The presence of the pan 39 prevents the waste from dropping through between the finger ends 20 and 72 when it is initially dropped between the assemblies 17 and 22, so that the waste will be engaged by the combs 70 and 71 immediately it leaves the pan 39 thus to be carried along between the fingers rather than tending to slide on downwardly therebetween until the waste is pulled apart and fluffed up sufficiently to maintain it between the assemblies until it is discharged over the fingers 19a and 24a at the discharge ends of those finger assemblies.

Thus it is to be seen that I have provided a very novel structure for the purpose intended, operating in a very simple but most effective manner. It is obvious that structural variations may be employed without departing from the spirit of the invention, and I therefore do not desire to be limited to that precise form as described, beyond the limitations which may be imposed by the following claims.

I claim:

1. In a waste shaker, a supporting structure; a pair of finger assemblies rockably carried in spaced apart relation by said structure; each of said assemblies comprising a plurality of spaced apart side by side fingers hanging generally downwardly; a pan rockably interconnecting fingers of each assembly at one end portion thereof; combs carried by fingers adjacent said pan; and means for rocking said assemblies one upwardly and the other downwardly as limited by said interconnecting pan.

2. In a waste shaker, a supporting structure; a pair of finger assemblies rockably carried in spaced apart relation by said structure; each of said assemblies comprising a plurality of spaced apart side by side fingers hanging generally downwardly; a pan rockably interconnecting fingers of each assembly at one end portion thereof and intermediate the upper and lower ends of the fingers; combs carried by fingers adjacent said pan; and means for rocking said assemblies one upwardly and the other downwardly as limited by said interconnecting pan; said assemblies being inclined downwardly from said end portion to a discharge end portion; said combs being confined to those fingers intermediate said pan and said discharge end portion.

3. In a waste shaker device, opposing finger assemblies, each assembly comprising an upper member to which upper ends of fingers are secured therealong in spaced relation to hang therefrom and terminate by lower free ends; a supporting structure; means rockably mounting said upper members on said structure in spaced apart relation to have said upper members substantially parallel; means rockably interconnecting said assemblies one with the other to have the fingers of one assembly at acute angles to the fingers of the other assembly in a normal, central, downward hanging of the fingers; and means for reciprocating said interconnecting means transversely of said upper members and thereby rocking said finger assemblies.

4. The structure of claim 3 in which waste combing means is carried in opposing relation longitudinally along fingers of each assembly intermediate the upper and lower ends thereof.

5. In a waste shaker device, opposing finger assemblies, each assembly comprising an upper member to which upper ends of a plurality of fingers are secured therealong in spaced relation and hang therefrom to terminate in lower free ends; a supporting structure; means rockably mounting said upper members on said structure in spaced apart, substantially parallel relation; waste receiving means interconnecting said assemblies intermediate said upper members and said free ends positioning the fingers of one assembly at acute angles to the fingers of the other assembly when the fingers are in central positions of rocking; means for rocking the assemblies transversely of said upper members; waste combing means carried in opposing relation longitudinally along said fingers of each assembly intermediate outer end fingers thereof; said upper member mounting means including arms offsetting the longitudinal axes of said fingers from the axes of rocking of said assemblies requiring the lifting and lowering of the free ends of said fingers in opposite directions during said rocking.

6. The structure of claim 5 in which said fingers have bottom ends turned from one assembly toward the fingers of the other assembly and those of one assembly being spaced apart from those of the other assembly throughout said rocking.

7. In a waste shaker device, opposing finger assemblies, each assembly comprising an upper member to which upper ends of a plurality of fingers are secured therealong in spaced apart, substantially parallel relation and hang therefrom with free ends; a supporting structure; means rockably mounting said members on said structure, one member substantially parallel with the other; a waste receiving pan rockably interconnecting said assemblies to have said fingers of one assembly disposed at acute angles to the fingers of the other assembly, and said pan having a length less than the over-all dimension transversely across all of said fingers; means for rocking the assemblies; and combs carried longitudinally along a number of the fingers of each assembly beginning at one edge of said pan and continuing in respect to fingers located therebeyond; said pan being located above the lower end of said comb carrying fingers.

8. The structure of claim 7 in which said assembly members are inclined, and said fingers of each assembly transversely positioned beyond said pan edge extend progressively to lower levels.

9. In a waste shaker device, opposing finger assemblies, each assembly comprising an upper member and a plurality of fingers secured therealong in spaced relation; a supporting structure; means rockably mounting said members in spaced apart relation on said structure; a waste receiving pan between and rockably interconnecting said as-

semblies below and at approximately equal distances from said members; combs carried longitudinally of and by a number of said fingers to one side of said pan; said pan being above the lower ends of said comb carrying fingers; said rocking means comprising a rod rockably connected to said pan centrally between assembly connected ends thereof; and means longitudinally reciprocating said rod.
